UNITED STATES PATENT OFFICE

WILLIAM D. HAILES, OF ROCHESTER, NEW YORK, ASSIGNOR TO GENERAL RAILWAY SIGNAL COMPANY, OF ROCHESTER, NEW YORK

TRAIN-CONTROL SYSTEM FOR RAILROADS

Application filed October 22, 1927. Serial No. 228,057.

This invention relates in general to train control systems, and has more particular reference to a system embodying a novel acknowledging means.

5 In train control systems employing cab signals it is undesirable to have flashing of the signals due to merely temporary changes in trackway conditions, such for example as occur at socalled dead sections of the track 10 as at switching points, cross overs, and the like.

It is usual in train control systems, whether they be of the intermittent or continuous type, to employ acknowledging means which 15 it is necessary to operate under certain conditions in order to avoid various penalties, such acknowledging means being provided to stimulate the engineer into being vigilant and alert at all times. It is usual however 20 to arrange the acknowledging means so that its operation is necessary only upon changes in traffic conditions from less to more restrictive conditions.

With the above and other considerations in 25 mind it is proposed in accordance with this invention to provide means to avoid the undesirable flashing of signals due to merely temporary conditions and also to provide an acknowledging means which will be much 30 more efficacious in stimulating the engineer into being alert at all times. More specifically, slow release relay means is provided for controlling the energizing circuit for cab signals whereby to hold a given indication 35 for some few seconds after track conditions have changed, to thus avoid a change of signal indication due to socalled dead sections and the like. With regard to the acknowledging means, it is proposed to so arrange 40 the same as to make it necessary to perform the acknowledging act upon every change in traffic conditions in order to avoid incurring a penalty. That is, the engineer must acknowledge on a change, for example, from 45 caution to clear conditions, as well as from clear to caution conditions, in order to avoid the penalty referred to.

Further objects, purposes and characteristic features of the invention will appear as 50 the description progresses, reference being

had to the accompanying drawing, showing, solely by way of example, one form which the invention can assume. In the drawing:

Fig. 1 shows, in a wholly diagrammatic manner, and without any attempt to show the particular form which is employed in practice, a system in accordance with the present invention. 55

Fig. 2 shows a modified form of the invention. 60

Referring to the drawing, a trackway circuit is diagrammatically indicated at 1, and is supplied, in the form shown, with coded track current in any desired manner, such for example as illustrated and described in 65 applicant's companion application for continuous train control system, Ser. No. 228,058, filed October 22, 1927. 65

Apparatus

Carried on the car is a receiver R, positioned to be inductively influenced by the coded track current and connected to the input side of an amplifying and rectifying device A. The output side of the device A is 70 connected to a decoding means Dec, while from the decoding means lead three wires 2, 3, 4 corresponding respectively to cab signals G, Y and R, indicating respectively in the usual manner clear, caution, and danger. 75 The amplifying and rectifying means and the decoding means can be of any desired type, such for example as shown in applicant's companion application referred to above, or his companion application, for 80 "automatic train control system," Ser. No. 228,059, filed October 22, 1927, the net result of the coaction between the receiver R, the trackway circuit 1, and the amplifier and decoder Dec, being to selectively place positive energy on one only of the wires 2, 3, or 85 4 in accordance with trackway conditions. 90

As it is essential to this invention only that energy be placed on the wires 2, 3 or 4 in a selective manner controlled in accordance 95 with trackway conditions, it will be obvious that various types of amplifiers and decoders can be used and likewise that the invention can be applied to either continuous or intermittent trackway systems, using either A. C. 100

or D. C. energy. If a continuous system be used it can be either plain continuous or coded continuous and if coded, a frequency code of a noncyclic character, or a cyclic code, 5 can be employed. See for example, applicant's companion applications, referred to above.

Corresponding to each of the cab signals G, Y, and R is a quick pick up but slow release stick relay GR, YR, and RR respectively, each of such relays controlling its particular signal through a contact finger 5, 6, and 7 and front contact, respectively. The system includes an acknowledging contactor *Ack.*, an acknowledging relay *Ack.* R., and a quick pick up but slow release control relay CR, which in conjunction with a speed controlled cam 8 and contact finger 9, operate to control an acknowledging 20 whistle valve AWV, and a train control device EPV.

The acknowledging whistle valve, AWV, when energized, gives an audible signal and is silent when de-energized. The train control device EPV may assume various forms, 25 depending upon circumstances, and is shown in the present case to be an electro-pneumatic device normally electrically energized and arranged when de-energized to give a train 30 control influence such as an automatic brake application, or the like, and, as shown, is supplied with a stick contact 10.

Operation

35 The various parts shown, and described above, are shown in their normal positions and conditions, that is, in the positions and conditions prevailing under travel in clear territory. Under such conditions, positive 40 energy is applied to wire 2, while the wires 3 and 4 are not energized. This results in signal relay GR being stuck up through a stick circuit including its contact finger 11 and front contact, to thereby complete an 45 energizing circuit for the signal G which includes contact finger 5 and front contact of relay GR. The acknowledging relay *Ack.* R., is energized through a circuit including contact finger 12 and front contact of relay 50 GR, and energization of the acknowledging relay completes an energizing circuit for the slow release control relay CR which includes contact finger 13 and front contact of the acknowledging relay *Ack.* R., and contact 14 and front contact of the acknowledging contactor *Ack.* With the armature of the 55 control relay CR in attracted position an energizing circuit for the train control device EPV is completed and includes contact finger 15 and front contact of relay CR, the device EPV, and stick contact 10 and front contacts of EPV.

Assume now for the purpose of explanation that there is a change in traffic conditions from clear to caution. Energy is now

taken off of wire 2 and applied to wire 3 through the operation of the decoding means *Dec.* A few seconds after energy has been removed from wire 2, the slow release relay GR releases to thereby break the energizing 70 circuit for signal G at contact finger 5, and to break the energizing circuit for relay *Ack.* R. at contact finger 12. De-energization of the acknowledging relay *Ack.* R. causes de-energization of control relay CR at contact 75 finger 13 and at the same time causes energization of the acknowledging whistle valve, AWV, at contact finger 16 and back contact of the acknowledging relay *Ack.* R., whereupon an audible signal is given. The control relay CR is designed to have a release time of about five seconds, so that the energizing circuit for EPV is not at once broken and hence a brake application is not at once incurred.

With the conditions just described if the engineer be alert and follow the indication given him by the acknowledging whistle, he operates the acknowledging contactor *Ack.* which operates to silence the acknowledging 90 whistle AWV by de-energizing it at contact 14 and front contacts of *Ack.* At the same time the contacts 17, 18, and 19 of *Ack.* close pick up circuits for the relays GR, YR, and RR respectively, whereupon, since energy is 95 on wire 3 only, relay YR only picks up, and is then stuck up through its contact finger 20 and front contact. Upon picking up of relay YR, the acknowledging relay *Ack.* R. is re-energized through a circuit including contact 100 finger 21 and front contact of relay YR, to thereby re-energize the control relay CR and maintain its contact finger 15 in attracted position, thereby preventing de-energization of the train control device EPV and the resulting 105 brake application. This acknowledging act, it is obvious, must be performed and completed within the drop away time of slow release control relay CR in order to prevent a brake application. The train can now proceed until another change in traffic conditions takes place, without further operation of the 110 various devices.

Let us assume, however, that the engineer is not alert, and does not operate the acknowledging contactor *Ack.* upon hearing the signal from AWV. After about five seconds, relay CR releases and train control device EPV is de-energized at contact finger 15 and front contact of relay CR, and opens a second point in its energizing circuit at its stick contact 10, the de-energization of device EPV causing an automatic brake application.

The penalty inflicted for failure to acknowledge thus consists in incurring an automatic brake application and the necessity for bringing the train to a predetermined low speed, in the present case 2 miles per hour, at which speed the cam 8 operates to close its contact finger 9, whereupon acknowledgment 125

in the manner described above will operate to pick up relay YR and thereby re-energize and pick up the acknowledging relay Ack. R, and in turn the control relay CR, whereupon the train control device EPV will be re-energized through a circuit including contact finger 15 and front contact of relay CR and contact finger 9 of the speed controlled cam 8, which latter it will be noted is arranged to shunt the stick contact 10 of EPV out of the energizing circuit for the train control device. Thus the acknowledging contactor Ack., operated in conjunction with the cam operated finger 9 when the train has been brought to a predetermined low speed, functions as a reset device to permit the train to be released from the brakes and allowed to proceed. It will be noted that the acknowledging contactor cannot be operated to prevent incurring the penalty, after the lapse of the release time of control relay CR from the time of a signal change since EPV is normally energized through the stick contact 10.

The operation of the system upon a change in traffic conditions from caution to danger is exactly the same as just described for a change from clear to caution, and what should be particularly noted, is that a change from caution to clear or from danger to caution requires acknowledgment in exactly the same manner as described above, in order to avoid the penalty. For example, if the train is proceeding under caution conditions and conditions clear up so that energy is taken from wire 3 and is applied to wire 2, unless the acknowledging act be performed within the specified time after the sounding of the acknowledging whistle, the control relay CR will release its contact finger 15 to de-energize EPV and give an automatic brake application.

Due to the slow release characteristic of each of the signal relays GR, YR and RR, after once having received a given trackway indication, such indication is stored up for a few seconds, i.e. during the release time of each relay, so that a merely temporary change in trackway conditions as for example a dead section, will not cause a flashing change of signal, unless its duration be greater than the release time of the relay in question. Such relays are, of course, designed to have a release time greater than the duration of such merely temporary changes.

In applicant's referred to application "Automatic train control system," during the continuance of the sending of any given code, as, for example, the G code, energy is placed on wire 2 and is left thereon continuously, whereby the signal G is kept steadily on under normal conditions. On traversing a dead section, or the like, however, energy is momentarily removed from the particular wire, 2, 3 or 4, as the case may be, this causing a

momentary blinking of the signal light, even though the control relay, as GR, still remains up.

Furthermore, when employing a code such as is shown in the referred to application entitled "Continuous train control system", during the continuance of sending of any given code, as, for example, the G code, energy is placed on wire 2, and removed therefrom, during each complete cycle of the code. This, as in the case of "dead sections", etc., referred to above, causes a blinking of the light signal in question.

It might be preferable, at least under some circumstances, to avoid the above discussed blinking of the signals, which, on analysis of the arrangement shown in Fig. 1, is primarily due to having the energy for operating the signals taken directly from the control wires 2, 3 and 4.

In Fig. 2 is shown an arrangement of parts, only slightly different from Fig. 1, for obviating blinking of the signal lights. In Fig. 2, the circuits for energizing the signals, and including the fingers 5¹, 6¹, and 7¹, are fed from local sources of energy, rather than from wires 2, 3, and 4, as in Fig. 1. In Fig. 2, the G signal is energized through a local circuit including the contact fingers and back points 7¹ and 6¹ of relays RR and YR respectively; the Y signal through a contact finger and back point 7¹ of relay RR; and the R signal through contact fingers and back points 5¹ and 6¹ of relays GR and YR respectively. Thus, so long as a signal control relay is attracted, when once the signal is energized, it so continues, regardless of momentary de-energization of its control relay.

It will be seen from the above that undesirable flashing of the signals due to merely temporary changes in trackway conditions has been effectually obviated and that the engineer will be constantly stimulated into alertness and vigilance by the necessity for performing the acknowledging act upon every change in signal indication, whether up or down, that is, whether from less restrictive to more restrictive conditions, or vice versa, in order to avoid incurring a penalty.

The above rather specific description of one form of the invention is given solely by way of example, and is not intended, in any manner whatsoever, in a limiting sense. Obviously, the invention can assume many different physical forms, and is susceptible of numerous modifications, and all such forms and modifications are intended to be included by this application, as come within the appended claims.

Having described my invention, I now claim:

1. In a train control system, car carried apparatus including, a plural aspect signal, means responsive to traffic controlled trackway influences for selectively energizing said

signal, a train control device initiated upon every change in signal aspect, and manual acknowledging means operable to prevent such initiation of said device.

5. In a train control system, car carried apparatus including, a plural aspect signal having aspects of varying restrictiveness, means responsive to traffic controlled track-way influences for selectively energizing said signal, a train control device initiated upon a change in signal aspect both to more, and to less, restrictive, acknowledging means operable to prevent such initiation of said device, and speed controlled means for permitting resetting of said device by the acknowledging means only when the speed is below a given value.

20. In a train control system, car carried apparatus comprising, a plural aspect signal, means for selectively energizing the signal in accordance with traffic conditions, a train control device initiated upon deenergization, an acknowledging means, and means for putting energy on the train control device when the acknowledging means is operated provided the train speed is below a given speed, means for deenergizing the device upon every change in traffic condition, the acknowledging means being operable to prevent said deenergization of said device.

25. In a train control system, car carried apparatus comprising, a plural aspect signal, means for selectively energizing the signal in accordance with traffic conditions, a train control device initiated upon deenergization, an acknowledging means, means for putting energy on the device, if the train speed is below a given speed, when the acknowledging means is operated, and means for deenergizing the device upon a change from more to less restrictive traffic condition, the acknowledging means being operable to prevent said deenergization of said device.

40. In a train control system, car carried apparatus comprising, a plural aspect signal, means for selectively energizing the signal in accordance with traffic conditions, a train control device initiated upon deenergization, an acknowledging means, means for putting energy on the device, if the train speed is below a given speed, when the acknowledging means is operated, means for deenergizing the device upon every change in traffic conditions, the acknowledging means being operable to prevent said deenergization of said device, and an acknowledging signal energized upon each change in traffic conditions and deenergized by the operation of said acknowledging means.

45. In a train control system, a plural aspect signal, and traffic responsive means for selectively energizing the signal including, a relay for each signal aspect distinctively energized in accordance with traffic conditions and

each controlling its signal aspect through a front point of the same, an acknowledging contactor accessible to the engineer during engine operation for simultaneously controlling a pick up circuit for each relay, and a stick circuit for each relay.

7. In a train control system, a plural aspect signal, and traffic responsive means for selectively energizing the signal including, a slow release relay for each signal aspect distinctively energized in accordance with traffic conditions and controlling its signal aspect through a front point thereof, a readily accessible acknowledging contactor for simultaneously controlling a separate pick up circuit for each relay, and a separate stick circuit for each relay.

8. In a train control system, a plural aspect signal, and traffic responsive means for selectively energizing the signal including, a relay for each signal aspect distinctively energized in accordance with traffic conditions and controlling its signal aspect through a front point of the same, an acknowledging contactor simultaneously controlling a pick up circuit for each relay, a stick circuit for each relay, a train control device initiated upon deenergization, and means energized through a front point of any one of said relays for preventing the initiation of the train control device.

9. In a train control system, a plural aspect signal, and traffic responsive means for selectively energizing the signal including, a relay for each signal aspect distinctively energized in accordance with traffic conditions and controlling its signal aspect through a front point thereof, an acknowledging contactor simultaneously controlling a pick up circuit for each relay, a stick train control device initiated upon deenergization, and means energized through a front point of any one said relays for preventing the initiation of the train control device.

10. In a train control system, a plural aspect signal, and traffic responsive means for selectively energizing the signal including, a relay for each signal aspect distinctively energized in accordance with traffic conditions and controlling its signal aspect through a front point thereof, an acknowledging contactor simultaneously controlling a pick up circuit for each relay, a stick circuit for each relay, a train control device initiated upon deenergization, means energized through a front point of each of said relays for preventing the initiation of the train control device, and an acknowledging signal sounded upon every change of traffic conditions and silenced upon operation of the acknowledging contactor.

11. In a train control system, a plural aspect signal, and traffic responsive means for selectively energizing the signal including, a relay for each signal aspect distinctively energized in accordance with traffic conditions and

energized in accordance with traffic conditions and controlling its signal aspect through a front point thereof, an acknowledging contactor simultaneously controlling a pick up circuit for each relay, a stick circuit for each relay, a stick train control device initiated upon de-energization, means energized through a front point of each of said relays for preventing the initiation of the train control device, and a speed controlled device operable below a predetermined speed to shunt the stick contact out of the energizing circuit of the train control device.

12. In a train control system, a plural aspect signal, and traffic responsive means for selectively energizing the signal including, a relay for each signal aspect distinctively energized in accordance with traffic conditions and controlling its signal aspect through a front point thereof, an acknowledging contactor simultaneously controlling a pick up circuit for each relay, a stick circuit for each relay, a train control device initiated upon de-energization, means energized through a front point of any one of said relays for preventing the initiation of the train control device, and a speed controlled device operable below a predetermined train speed to shunt the stick contact out of the energizing circuit of the train control device.

13. In a train control system, car-carried apparatus, including, a plural aspect signal, means responsive to traffic controlled track-way influences for selectively completing energizing circuits for said signal, a local energy source, separate from said means, for energizing said energizing circuits, a train control device initiated upon every change in signal aspect, and acknowledging means operable to prevent such initiation of said device.

In testimony whereof I affix my signature.
WILLIAM D. HAILES.
